UNITED STATES PATENT OFFICE.

WILLIAM LOOMIS ALLEN, OF JACKSONVILLE, FLORIDA.

SIGNALING MEANS.

Specification of Letters Patent.

Patented Mar. 4, 1919.

1,296,253.

Application filed February 28, 1918. Serial No. 219,713.

To all whom it may concern:

Be it known that I, WILLIAM LOOMIS ALLEN, a citizen of the United States, residing at Jacksonville, in the county of Duval and State of Florida, have invented certain new and useful Improvements in Signaling Means, of which the following is a specification.

This invention relates to signaling means, and more particularly to an indicating mechanism especially adapted for use in connection with automobiles and similar vehicles.

One of the main objects of the invention is to provide a signaling means of simple construction and operation which may be readily applied to an automobile of standard construction. A further object is to provide a signaling means of very simple and efficient operation which may be produced at small cost. Another object is to provide a signaling means consisting, essentially of a casing and a cylinder rotatably mounted therein, the casing having a transparent pane or closure member and the cylinder being provided with suitable indicating marks on its peripheral surface. A further object is to provide a casing and a cylinder related in the manner set forth, the transparent closure member being secured to the cylinder in such a manner as to permit the ready removal thereof while insuring a tight closure between this member and the cylinder so as to exclude dust, grit and other foreign material from the casing. Further objects will appear from the detailed description.

In the drawings:

Figure 1 is a diagrammatic view of a signaling device constructed in accordance with my invention as applied to an automobile.

Fig. 2 is a view in elevation of the signaling device proper.

Fig. 3 is an end view.

Fig. 4 is a plan view of the indicating disk and operating lever.

Fig. 5 is a view in elevation of the casing.

Fig. 6 is a similar view of the cylinder.

Fig. 7 is a fragmentary section through the casing.

The signaling device, broadly stated, comprises a casing in which is rotatably mount-

ed a cylinder, this cylinder being provided with suitable indications on its peripheral surface, which are adapted to be moved into alignment with a transparent closure member interposed in the casing, the cylinder being readily removable from the casing for repairs or so as to permit the insertion of a new cylinder. The casing 1 is of cylindrical shape, being formed from sheet metal of suitable gage. This casing is provided with a relatively broad slot extending the full length thereof. This slot is closed by means of a transparent closure member 2, of such width and length as to project beyond the edges of the slot in the casing, which is interposed between the outer surface of the slot in the cylinder and the rectangular securing frame 3 which may also be formed of sheet metal. The side bars 3^a of frame 3 are each provided, on its inner face, with a packing strip of felt or other suitable material. Similar packing strips 4 are secured to the outer face of the casing 1 adjacent each side of the openings. These packing strips co-operate with the packing strips carried by the side bars 3^a of the frame 3 to form a tight closure about the edge portions of the transparent closure member 2, thus effectually excluding all entry of dust or other foreign material into the casing 1 about the sides of this frame.

A closure disk 5 is secured in one end of casing 1. This disk is provided at its center with an inwardly extending stud bolt 6 secured therein. This bolt fits into one end of the cylinder 7 which is mounted in the casing, this cylinder corresponding in length with the interior of the casing, approximately. This cylinder is provided, at its other end, with a stud shaft 8 secured at the center thereof and disposed in axial alignment with stud bolt 6. A double or two-grooved pulley 9 is mounted on stub shaft 8 and secured thereto by a set screw 10 threaded through the sleeve 11 of the pulley. This pulley acts to prevent the removal of the end disk 12 through which the stub shaft 8 is loosely inserted. This end disk fits snugly in the other end of the casing 1 so as to form a closure member therefor. The end of frame 3 adjacent the end

of the casing in which disk 5 is mounted is tightly secured in position by means of a securing band 13 which is passed about the end of the cylinder. This band is provided at each end with an integral outwardly directed ear 14, and these two ears are provided with alined openings which receive a securing bolt 15 on which is threaded a nut 16. By this means, the band is secured tightly about the cylinder so as to releasably secure the end of frame 3 thereto. The other end of frame 3 is similarly secured to the cylinder by a band 17, this latter band also serving to force the end 14 of the casing into tight engagement with the peripheral surface of disk 12 thus securing the disk in the casing. Suitable packing strips are provided at each end of the frame 3 between the end bars thereof and bands 13 and 17 and disks 5 and 12, respectively. By this means, the transparent closure member is secured to the casing so as to be readily removable therefrom, the means for securing one end of this member also serving to secure the cylinder within the casing in such a manner as to permit ready insertion or withdrawal of the same therefrom. When it is desired to remove the cylinder, or to insert a new cylinder, this may be readily accomplished by slightly loosening band 17, without the necessity of removing or completely detaching either end of frame 3 for the transparent closure member. When this band has been slightly loosened, the disk 12 may be readily removed, permitting the cylinder to be drawn out of the casing and be reinserted thereinto, or a new cylinder to be substituted. In the latter case pulley 9 may be readily removed from stud shaft 8 by loosening the set screw 10, thus permitting removal of disk 12 from the shaft, the pulley being secured on the stub shaft of the new cylinder which is placed in the casing. The securing bands 13 and 17 also pass about a bracket plate 18. This bracket plate is of arcuate cross section being curved to correspond with the curvature of casing 1 so as to fit snugly thereon. Plate 18 is provided, at each side, with an off-set arm 19 which is apertured to receive securing bolts 20, a nut 21 being threaded on each bolt so as to secure one end of a bracket arm 22, to arm 19, the other end of arm 22 being secured to a suitable supporting base 23. By means of the bracket plate and arm, the casing may be readily secured to the body of the vehicle in any desired position.

The peripheral surface of the cylinder 7 is provided with a plurality of suitable markings or indications thereon such as "Stop," "Back," "Right" and "Left." It will be obvious that, by turning the cylinder in the desired direction, any one of the several designations may be brought into alignment with the openings in front of which

is positioned the transparent closure member 2, so as to be easily visible. To effect this result, I provide the indicating disk 24 which may be mounted on the steering standard of the automobile with the device in use, or in any other suitable position so as to be readily accessible. A stub shaft 25 is inserted through the center of the disk 24, and a suitable operating handle 26 is secured to the outer end of this stub shaft. A grooved pulley 27 is secured on the inner end of the shaft 25. This pulley is of such diameter, that, when it is turned so as to bring the handle 28 into register with any of the indications on the disk 24, if a cable is passed about this pulley and pulley 9, the cylinder 7 will be rotated such a distance as to display the corresponding indication through the transparent closure member 2. In practice, I prefer to use two signaling devices, one at the front, and the other at the back of the automobile, the signaling devices being connected by a common cable 28 which is passed about the pulley 27. By turning the handle 26 a driver of an automobile will display a signal at each end of the vehicle so as to indicate clearly to vehicles in front and in back of him in which direction he is contemplating turning, if he wants to make a turn, or what other action he is going to take.

To insure proper operation of the indicating means described, I provide means whereby the cable 28 may be maintained under constant tension so as to properly grip the pulley 9. For this purpose, a bolt 29 is interposed in the cable, this bolt being inserted through the cross bar of a stirrup 30 which is secured to one end of the cable, a similar stirrup 31 being secured to the other end of the cable and receiving the shank of the bolt on which is threaded a nut 32 positioned adjacent the inner face of the cross bar of the stirrup 31. By threading this nut on to the bolt, the cable may be tensioned as described.

To render the signal given readily visible at night, I provide means whereby a light may be supported adjacent the transparent closure member 2. A spring clip is secured on the casing 1 and is adapted to receive a socket 33 which supports a lamp 34 having the reflecting hood 35. This clip is so positioned that the lamp is above and in front of the closure member 2, the light rays being reflected directly on to this member thus rendering the signals given easily visible.

What I claim is:

In a signaling device of the character described, a cylindrical casing, a disk secured in one end thereof, a cylinder rotatably mounted in said casing and provided in one end with an outwardly projecting stub shaft, a closure disk loosely mounted on said stub

shaft and adapted to fit in the other end of said casing so as to close the same, a pulley demountably secured to said stub shaft outside of the second mentioned disk, and means for releasably securing the closure disk carried by said stub shaft in the other end of the casing.

In testimony whereof I affix my signature in presence of two witnesses.

WILLIAM LOOMIS ALLEN.
